(57) **CLAIM**

I claim the ornamental design for a spray dispenser, as shown and described.

DESCRIPTION

FIG. 1 is a front perspective view of the spray dispenser; FIG. 2 is a front elevational view of the spray dispenser; FIG. 3 is a top plan view of the spray dispenser; FIG. 4 is a right side elevational view of the spray dispenser, the left side elevational view being a mirror image; and, FIG. 5 is a rear elevational view of the spray dispenser. The left side of the spray dispenser is symmetrical with the right side shown in FIG. 4.

The broken lines in the drawings are for illustrative purposes only and form no part of the claimed design.
